UNITED STATES PATENT OFFICE.

ALFRED WALTER MALEY, OF WEST BROMWICH, ENGLAND.

MANUFACTURE OF ELECTRICAL RESISTANCES.

1,088,157.

Specification of Letters Patent. Patented Feb. 24, 1914.

Application filed October 8, 1910. Serial No. 586,030.

To all whom it may concern:

Be it known that I, ALFRED WALTER MALEY, a subject of the King of Great Britain, residing at 200 Beeches road, West 5 Bromwich, in the county of Staffordshire, England, have invented new and useful Improvements in the Manufacture of Electrical Resistances, of which the following is a specification.

The invention relates to electrical resistances such as starting resistances for motors, regulating resistances for generators, and for all those purposes where the use of this type is advantageous. These resistances are 10 now commonly made in the form of grids which have as a rule been cast in iron. Such cast grids are fragile and on account of the irregularities inseparable from cast material are unreliable. Recently grids have been 15 stamped out of sheet mild steel to avoid the objection of unreliability, but the resistances thus made are inconvenient because the small specific resistance of the mild steel necessitates the use of a very considerable 20 number of grids which occupy a large space and increase the possibility of breakdown at joints. The use of the resistant alloys already known is hindered by their high price, this difficulty being accentuated by the fact 25 30 that resistances of such alloys would have to be of considerable section in order to take the large currents employed without undue heating.

According to the present invention a steel 35 or iron containing a high percentage of carbon is employed for the resistances, this material having a resistance approaching that of the cast iron hitherto used. A steel of this kind is hard and therefore in the larger 40 sections very difficult to work in the ordinary state, but this difficulty may be overcome in several ways.

In the first place, the steel may be used in the form of wire of any convenient section. 45 This wire may be bent when hot into the form of a grid but it is somewhat difficult to maintain the necessary heating. Instead of winding the material hot, wire of soft steel may be wound or a soft steel plate may 50 be stamped into the form of the grid, and this material may then be hardened by carbonization by the well known process of case hardening. Of course, the hardening is effected not for its own sake but because of 55 the increase in specific resistance resulting from the addition of carbon.

With wires of small section it may be possible to wind the hard material itself cold.

It is a feature of the invention that when grids are thus made either by forming wire 60 which is preferable or by stamping from sheet metal, it is possible to avoid joints to a large extent or even completely, for a large number of grids may be stamped in one piece from a sheet of metal wound from 65 a single length of wire, and the grid thus produced bent upon itself so as to make the necessary succession of grids to mount in a box or frame. Obviously this method of manufacture may be adopted with any material capable of being formed or stamped.

In the drawings in which is illustrated one form of resistance grid constructed in this manner, Figure 1 is a front elevation. Fig. 2 is a plan while Fig. 3 is a side elevation and Fig. 4 illustrates an alternative 70 method of forming such a grid.

Referring to Figs. 1 to 3, in which the same reference letters refer to corresponding parts, the wire *a* of the proper cross-section is wound into a continuous zig-zag in the manner of a series of grids as seen in Fig. 1. Successive sections are then bent parallel or approximately parallel to each other as best shown in Fig. 2, the wire being twisted 75 at the bend so that the depending loop *c* is flat on its outer surface to receive terminals at the bends for tappings to external circuits. The grids are supported on bolts 80 *b* surrounded by insulating tubes *c* and are 85 separated from each other by insulating washers *d*. The bolts *b* are clamped at their ends by means of nuts to a pair of parallel frame plates.

Where the resistance is formed it is not 90 necessary to adhere to the grid type, although this is the best known and is very compact. Instead the wire or rod can be wound in flat coils, but this has the disadvantage that one end is in the middle. Flat 95 coils may be formed in another way by winding the strip over a sheet, which avoids 100 this disadvantage, the sheet being removed so that the resistance is surrounded by air. Such coils may be mounted in the same way 105 as the known type of grid.

In stamping the grids difficulty is encountered in the fact that the strength necessary for the stamping tool determines its size, and this again determines the size of 110 opening between successive turns of the grid. This becomes particularly important

when material of higher specific resistance is employed, for a greater thickness is required and a more substantial tool becomes necessary. To overcome this difficulty the 5 grid may be stamped as a simple sinuous strip *g* (Fig. 4) which will allow of the use of adequately large tools even for the stamping of fairly thick or hard material. As 10 shown, a strong wedge-shaped tool may operate between the side members *h*. The sinuous strip *g* thus formed can be closed up so that its turns lie close beside one another as in the ordinary grid, and of course 15 continuous grids as shown in Figs. 1 to 3 may be formed in this fashion.

What I claim is:—

1. A multiple-unit rheostat, comprising a series of units forming a continuous integral conductor, each unit comprising a grid having terminal loops constituting attaching means and terminal connectors.
2. A multiple-unit rheostat, comprising a series of units forming a continuous integral conductor, each unit comprising a grid hav-

ing terminal loops constituting attaching 25 means and terminal connectors, and the units being arranged side by side and forming parallel grids connected at their ends to the adjacent units by means of said terminal loops.

3. A multiple-unit rheostat comprising a continuous integral conductor formed into a succession of loops and bent upon itself at intervals to constitute a compact series of parallel grids, interconnected by terminal portions, said terminals being formed into loops to thereby provide attachments for terminal connections.

4. A rheostat comprising a continuous conductor of iron having a carbon content 40 concentrated toward the exterior.

In testimony whereof I have signed my name to this specification in the presence of two subscribing witnesses.

ALFRED WALTER MALEY.
